UNITED STATES PATENT OFFICE.

HENRY E. SMITH, OF CHICAGO, ILLINOIS.

AWNING.

Application filed April 16, 1926. Serial No. 102,378.

The object of my invention is to provide new and improved means for mounting awnings, and also for holding them in normal extended position. With these objects in view my invention consists in the matters hereinafter described and pointed out in the appended claims.

In the accompanying drawing, Figure 1 is a perspective view of an awning embodying the features of my invention and mounted in position for use, only part of the window-casing being shown; Fig. 2 is a detail side view with parts broken away; Fig. 3 is a detail front view of the frame-fixture with parts of the frame in section on the line 3—3 in Fig. 2; and Fig. 4 is a detail sectional view on the line 4—4 in Fig. 2.

The reference numeral 1 indicates a spring-roller mounted in suitable brackets 2 secured upon the outside of a window-casing 3, usually at or near the line where the upper and lower sashes meet. The awning-cloth, consisting of a suitable length of canvas or other material, is connected intermediate its ends to the roller so that its upper and lower sections 4 and 5 will wind thereon. The lower section 5 is attached at its free end to the cross-piece of a bowed metallic frame 6, which is pivotally mounted 30 at its ends on the window-casing, and the upper section 4 has a head-rod 7 to which an operating cord 8 is connected and passed over one or more pulleys 9, according to whether it is extended down on the outside 35 of the window or through the window-casing into the room. The free end of the cord may be suitably fastened either inside or outside the window to hold it in any desired position. When the cord is drawn up the upper 40 section 4 of the awning-cloth is extended or drawn upwardly to the position shown in Fig. 1, the roller is revolved to place its spring under tension and unwind the lower section 5 of the cloth, and the frame 6 swings 45 down by gravity to its extended position. When the cord is released the spring-roller automatically winds up the sections of the awning cloth to withdraw them from their extended positions and to swing the frame 50 6 up to position alongside the window-casing below the roller.

The frame 6 is detachably secured to the window-casing by devices which permit it to be attached and detached without swinging the frame down below its normal extended position. In this type of awning as here-

tofore constructed hooks on the free ends of the frame engaged supports on the casing, and in order to prevent disengagement of the hooks by the wind blowing the awning upwardly it was necessary to extend or prolong the ends of the hooks around their supports, and consequently the hooks could be engaged thereon only when the frame was swung down below its normal extended position to permit the hooks to pass onto their supports from above. This is objectionable as it requires unrolling the awning-material which is then cumbersome and difficult to handle. I obviate this objection by providing the frame 6 with end eyes or loops 10 which pivotally engage opposite pintles 11 extending laterally from brackets 12 on the casing. The free ends of the pintles are reduced, and gravity latches 13 of approximately the same diameter as the pintles are pivoted thereon intermediate their ends but offset from their centers as shown at 14; when the latches are turned to align with the pintles the loops 10 may be easily slipped on or off the latter, and when the latches are released they will turn by gravity to position to block the loops and hold them on the pintles. This construction simplifies the installation and removal of the awning, as it 80 may be put up or taken down while the cloth is wound on the roller and the frame is in one of its normal positions.

The frame 6 is held in its extended position by a friction lock which has sufficient grip to prevent the lower section of the awning being blown upwardly by the wind, but which readily yields to the superior strength of the spring of the roller when the cord is released to permit the latter to revolve. In the form here shown, annular metallic collars 15 are slidably mounted on the side arms of the frame 6, and each collar is provided with upwardly projecting ears 16 in which one end of a link 17 is pivoted, the other end of the link having a downwardly opening hook 18 to engage the cross-pin 19 of a jaw-hinge 20 on the casing above the bracket 12. Each collar is provided with a chamber in which a friction ball 21 is located and held by an expansion spring 22 in contact with the associated side arm of the frame 6, which is provided with a recess or notch 23 so located that the ball engages it when the frame is in its extended position. Each ball and spring are held in place by a cap 24, and the pair of springs

for each frame is of less strength than the roller-spring. When the frame and awning are extended by the cord 8 the balls engage the notches and hold the lower section 5 against flapping or being blown upwardly by the wind. When the cord is released the superior strength of the roller-spring overcomes the resistance of the relatively weaker springs 22 and the roller winds up the awning and swings the frame 6 upwardly. The links move the collars inwardly and outwardly on the sides of the frame as the latter swings on its pivots.

The pivotal bracket 12 and jaw-hinge 20 for each side of the frame are mounted in line on a base 25 which is screwed to the window-casing; each base and its bracket and jaw-hinge constitute a unitary fixture on which one side of the frame 6 and its associated link 17 are detachably supported, and all these parts can be positioned by merely engaging the hooks 18 with their pins 19 and the eyes 10 with their pintles 11, and can be removed by merely disconnecting the same. Both operations can be accomplished with the awning-cloth wound on its spring-roller. The fixtures provide a permanent assembly for each pair of brackets and jaw-hinges, it being understood that the construction and arrangement of the various parts are the same on each side of the awning.

I claim:

1. In a device of the class described, an awning, a swinging frame therefor pivotally mounted at its ends on a window-casing and having a recess in one of its arms, a collar slidably mounted on said arm, a link pivotally connected to the collar and casing, a pressure member in the collar in line with said recess when the frame is extended, and a spring in the collar adapted to force the pressure member into engagement with the recess.
2. In a device of the class described, an awning, a swinging frame therefor pivotally mounted at its ends on a window-casing and having a recess in one of its arms, a collar slidably mounted on said arm and having a chamber in line with said recess when the

frame is extended, a link pivotally connected to the collar and casing, a ball in the chamber, and a spring in the chamber adapted to force the ball into engagement with the recess.

3. In a device of the class described, an awning composed of upper and lower sections connected to a spring-roller adapted to be revolvably mounted on a window-casing, a swinging frame connected to the free end of said lower section and adapted to be pivotally mounted at its ends on the window-casing and having a recess in one of its arms, a collar slidably mounted on said arm, a link pivotally connected to the collar and casing, a pressure member in the collar in line with said recess when the frame is extended, and a spring in the collar of less strength than the spring in the roller and adapted to force the pressure member into engagement with the recess.

4. In a device of the class described, a swinging awning frame having an eye, a collar slidably mounted on the frame, a link pivotally connected at one end to the collar and having a downwardly opening hook at its other end, means to yieldingly hold the collar in position on the frame when the latter is extended, and a unitary fixture for the eye and hook of the frame comprising a base, a pivotal support at the lower end of the base for the eye, and a pin at the upper end of the base for the hook.

5. In a device of the class described, a swinging awning frame having an eye, a collar slidably mounted on the frame, a link pivotally connected at one end to the collar and having a downwardly opening hook at its other end, and a unitary fixture for the eye and hook of the frame comprising a base constructed to be mounted on a window casing, a lateral pintle at the lower end of the base having a pivoted latch for the eye, and a pin at the upper end of the base for the hook.

In testimony whereof I hereto affix my signature.

HENRY E. SMITH.
